UNITED STATES PATENT OFFICE.

CLARENCE C. TRAVIS, OF CHICAGO, ILLINOIS.

DESIGN FOR A FACE-PLATE FOR VENDING-MACHINES.

No. 38,762.

Specification for Design.

Patented Aug. 20, 1907.

Application filed April 11, 1907. Serial No. 367,715. Term of patent 7 years.

To all whom it may concern:

Be it known that I, CLARENCE C. TRAVIS, a citizen of the United States, residing at Chicago, in the county of Cook and State of Illinois, have invented a certain new and original ornamental Design for a Face-Plate for Vending-Machines, of which the following is a specification, reference being had to the accompanying drawing, forming a part thereof.

I claim—

The ornamental design for face plate for vending machine, as shown.

CLARENCE C. TRAVIS.
